(57) **CLAIM**

The ornamental design for a one handed game controller, as shown and described.

DESCRIPTION

FIG. 1 is a top perspective view of the one handed game controller.

FIG. 2 is a top view of the one handed game controller.

FIG. 3 is a bottom view of the one handed game controller.

FIG. 4 is a right side view of the one handed game controller.

FIG. 5 is a left side view of the one handed game controller.

FIG. 6 is a front side view of the one handed game controller; and,

FIG. 7 is a rear side view of the one handed game controller.

The broken lines used in the Figures depict a functional optical sensor located on the bottom of the one handed game controller and light emanating from said optical sensor and neither forms any part of the claimed design. Gray is used as surface shading to represent a contrast in appearance and is not a claimed color of the design.
